INVENTOR:

John Q. Adams
BY
Eugene Ayres,
ATTORNEY,

UNITED STATES PATENT OFFICE.

JOHN Q. ADAMS, OF ST. JOSEPH, MISSOURI.

COMBINATION WORK-GARMENT WITH DETACHABLE JACKET.

1,183,511.

Specification of Letters Patent. Patented May 16, 1916.

Application filed September 20, 1915. Serial No. 51,735.

To all whom it may concern:

Be it known that I, JOHN Q. ADAMS, a citizen of the United States of America, residing at St. Joseph, in the county of Buchanan and State of Missouri, have invented certain new and useful Improvements in Combination Work-Garments with Detachable Jackets, of which the following is a specification.

- 10 The object sought by me in this invention is to provide a combination two piece work garment especially adapted to the use of mechanics and other classes of laboring men.
- 15 I accomplish my object by the construction shown in the accompanying drawings, in which—

Figure 1 is a front view of said garment the sleeves and a portion of the collar broken away; Fig. 2 is a similar view showing the two pieces detached, and Fig. 3 is a detail of a tab on the inside of the back of the jacket, a buckle, a self adjustable suspender therein and a protector with a loop thereon.

Similar letters refer to corresponding parts in the views shown, A representing a pair of trousers and B a jacket detachable therefrom.

20 C is a front waist band and C' a back waist band, both front and back bands being provided with a plurality of buttons . . . . Each side of said trousers is provided with a slit or opening D, and with 25 front swinging pockets D' D' and a watch swinging pocket d. Said trousers are also provided with an opening E at the front extending from the crotch to waist band C and with two hip patch pockets H H and 30 with a rule patch pocket H'. On the back of the waist band I attach two corresponding belt straps h h by which to tighten the trousers thereby obviating, when preferred, the use of both suspenders and belt. The 35 jacket is provided with a collar I and an extension collar band I', as shown in Fig. 1 at the point where said collar is broken away, forming connection with the band underneath the collar by means of button and button hole. Said jacket B is open at the front from the collar to the waist band.

K is a detachable suspender as shown in all the figures. L is a tab fastened at the top to the inside of the back of the jacket. 55 Said suspender K forms connection with

said tab by means of a buckle M or other suitable means.

To protect the body of the wearer from the rub of a suspender buckle I attach in conjunction with the tab a protector M' to 60 the inside of the back of the jacket. I also attach on the observe side of the bottom of said protector a loop O through which the suspender may slide the suspender thereby holding the protector in position. 65

The front of the jacket is provided at the waist band with a plurality of loops O' O' . . . with which a corresponding plurality of buttons O² O² . . . on the front waist band of the trousers engage. The 70 buttons on the back waist band of the trousers are adapted to engage with the back ends of the suspenders, said forward buckle and loop engaging with the forward end of the suspender. The back of the jacket is 75 provided with a curtain R extending slightly below the back waist band of the trousers. Said curtain is provided on each front edge with a tab R' which makes connection at an opening D by a snap fastening 80 or other suitable means.

From the above description it will be seen that by my construction of said garment I provide a jacket that may be readily and quickly detached from both the front and 85 back waist bands of the trousers.

What I claim and desire to secure by Letters Patent is:

1. In a garment of the kind described, the combination with a jacket and a curtain 90 integral with the rear thereof extending slightly below the waist band of the trousers, a tab on each front edge of said curtain suitably connected at the rear edge of each slit in the side of the trousers, of a tab attached on the inside of the back of the jacket, a detachable and adjustable buckle thereon, a single suspender looped loosely in said buckle its duplicate ends engaging with buttons on the outside of the 95 back waist band of the trousers and a protector attached to the inside of the back of the jacket adapted to drop in front of said tab and buckle and protect the back from unpleasant pressure of the buckle. 100

2. In a combination work garment with a detachable jacket having a front opening, a tab securely fastened on the inside of the back of the jacket, a buckle detachable and adjustable on said tab, a protector forward 110

of said tab and buckle, a loop on the reverse side of said protector near the bottom thereof, a suspender adjustable and detachable from both the rear waist band and the 5 tab to hold said protector in position, the ends of the suspender diverging into connection with buttons on the trousers, back waist band.

3. The combination in an open front 10 jacket and trousers with a trousers waist band having a plurality of buttons on the outside of the back of the waist band to engage suspenders and a front opening in said trousers from crotch to waist band, of a 15 detachable suspender, a tab securely fastened on the inside of the back of the jacket, a hinged buckle detachable from said tab and a loop thereon from which said suspender is detachable thereby forming a com-

bination detachable buckle and suspender, a 20 flap forming a protector in conjunction with said tab to obviate wear and protect the back of the wearer, a loop on the reverse side of the bottom of said protector through which the suspender slides and holds the protector 25 in position, a plurality of loops on the inside of the front of the jacket waist band having connection with a corresponding plurality of buttons on the outside of the waist band of the trousers, thereby rendering said jacket detachable at the front from said trousers. 30

In testimony whereof I affix my signature in the presence of two witnesses.

JOHN Q. ADAMS.
